US0D1069714S

(12) **United States Design Patent** (10) Patent No.: **US D1,069,714 S**
(45) Date of Patent: ** Apr. 8, 2025

(54) **TERMINAL FITTING**

(71) Applicant: **YURA CO., LTD.**, Hwaseong-si (KR)

(72) Inventors: **Soo Hwan Park**, Incheon (KR); **Woo Jae Gahng**, Seoul (KR)

(73) Assignee: **YURA CO., LTD.**, Hwaseong-si (KR)

(**) Term: **15 Years**

(21) Appl. No.: **29/825,706**

(22) Filed: **Feb. 4, 2022**

(30) **Foreign Application Priority Data**

Aug. 17, 2021 (KR) 30-2021-0038786

(57) **CLAIM**

The ornamental design for a terminal fitting, as shown and described.

DESCRIPTION

FIG. 1 is a perspective view of a terminal fitting, showing my new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof; and,

FIG. 8 is another perspective view thereof.

Portions of the terminal fitting shown in broken lines form no part of the claimed design.

1 Claim, 6 Drawing Sheets
